METHOD OF MAKING REFLECTING DEVICES

Edwin R. Gill, Jr., Yonkers, N. Y., assignor to
 Prismo Holding Corporation, New York, N. Y.,
 a corporation of New York

Application March 30, 1937, Serial No. 133,788

1 Claim. (Cl. 88—105)

This invention relates to the manufacture of reflecting devices, including signs when that term is used in its broadest aspect and includes any marker, signal device or mechanism which may be employed to attract attention or convey information, and irrespective of whether they may be in the form of independent units or constructed upon an already existing base, such as a wall, a pavement, etc., and has special reference to signs of the kind employing reflex reflecting elements forming the subject matter of an earlier invention of mine for which U. S. Letters Patent No. 1,902,440 were issued on March 21, 1933, and with respect to which the present invention constitutes in part an improvement.

I have discovered that in the construction of such signs, particularly when under circumstances where there is not the opportunity to use a baked enamel as a binder for glass reflex reflecting elements as, for instance, where the sign or marker has to be constructed in situ as on the pavement of a highway, or where for any other reason it is inconvenient to use a baked enamel and an air drying paint or enamel has to be used, a more close and permanent bond between the reflex reflecting elements and the binder, in a way that will preserve the sign for a longer time from wear and disintegration, may be obtained by a novel and improved form of such signs and methods of making it which involve making the reflex reflecting elements out of plastic material of the kind known as synthetic resin, such as the formaldehyde phenolic resins, formaldehyde urea resins, glycerine resins, or the like, whether of the condensation type or of the polymerization type, and embedding them in a binder consisting of a paint, lacquer or other substance containing a varnish gum of the same or similar resin out of which the reflex reflecting elements are made.

A further object of my invention is to provide a new method of making a reflecting device which will reflect light in a direction parallel to the incident rays and which has improved optical characteristics.

Another object of my invention is to provide a method whereby in such a device both the reflex reflecting elements and the binder in which they are embedded will form an integral mass, thus possessing an advantage over a reflecting device or reflex reflective sign composed of glass spheres embedded in a reflective binder of ordinary air-drying paint or enamel. The respective coefficients of expansion of glass and such air-drying paints and enamel are usually differ-

ent and where such a sign is subject to the varying degrees of temperature due to changes of weather, the composite structure will have a tendency to become weakened and the binder to separate from the spheres and permit them ultimately to work loose.

Other objects and advantages of my invention will appear from the following description of it and by reference to the accompanying drawing in which:

Fig. 1 is a plan view of a sign embodying my invention.

Fig. 2 is a cross sectional view greatly magnified of a portion of the sign shown in Fig. 1.

Fig. 3 is a cross sectional view of such sign constructed upon the surface of a highway.

Fig. 4 is a sectional view of a mold for making spherical reflex reflecting elements of plastic material.

Fig. 5 is a sectional view of an improved form 20 of a reflex reflecting element.

Fig. 6 is a sectional view of the reflex reflecting element shown in Fig. 5 mounted in a perforated base.

Fig. 7 is a side view of the reflex reflecting element shown in Fig. 6.

Referring to the drawing in which the same reference numerals are used to designate similar parts, 1 is a base which may be of any suitable material adapted to provide a supporting surface for the other materials out of which the sign is made, and where the sign is an independent unit (Fig. 1) it may be preferably of steel painted in any desired ground color or where the sign is constructed upon the surface of a highway (Fig. 3) it may be the material itself, such as concrete, of which the upper surface of the highway is composed. Upon this base is delineated any desired insignia by the application thereto of a binder coat 2 of paint, lacquer or other fluid substance containing a varnish gum capable of integrating by polymerization or hardening with the synthetic resin particles thereafter to be applied. Said varnish gum is of the same or similar resin out of which the reflex reflecting elements are made and if said varnish gum is of the permanently soluble class, such for instance as depolymerized formaldehyde-phenolic resin, it may be either of the alcohol-spirit soluble classification or of the benzine-oil soluble classification. Liquid resin itself may be used. Said coating may be made in any desired color by the addition of suitable pigment provided it is reflective of light.

Before this coat is dry and while it is still

soft, there is spread upon it a layer of reflex reflecting elements consisting of minute spherical transparent particles 3 composed of a synthetic resin such as phenol-formaldehyde or urea-formaldehyde more or less completely polymerized which are embedded in said coat to a depth of approximately one-half their diameter. The spheres will have a tendency to become embedded in the coating as a result of gravity, capillary 5 attraction or such embedment may be accomplished either by hand or by the use of a roller or other suitable means. It is important that the spherical particles be as small as possible and lie close to each other so as to avoid any dark 10 or dead spaces in the surface of the insignia 15 and to refract and reflect as much light as possible.

As the said binder coat hardens it will unite with the embedded portions of the spheres and 20 upon completion of the hardening process the binder and spheres will have become completely united together in an integral mass. I have found that where the said binder coat is compounded so as to produce a paint or lacquer of 25 normal brushing consistency the extent of its reaction on the embedded surfaces of the spheres will in no way diminish their reflex refracting quality and will only result in producing a permanent bond or weld between the spheres and 30 the binder coat. The spheres may be colorless and the reflective binder may be white or given a desired color or the spheres themselves may be given any desired transparent color. An additional protection against the moisture and the 35 elements may be given to the sign by coating the finished sign with a protective transparent waterproof coating such as a transparent lacquer, varnish or other like substance.

These minute spherical particles composed of 40 synthetic resin may be manufactured in any appropriate way either by using a ground synthetic resin in the form of a molding powder which may be charged into polished metal dies in a proper molding press or they may be cast from 45 liquid synthetic resin in a mold such as is shown in Fig. 4 in which the two halves 4 and 5 composed preferably of glass are each formed on their contacting faces with a number of hollow hemispheres 6 and 7 communicating with each other 50 by small passages 8. When the two halves of the glass mold are put together with the hollow hemispheres opposed the spherical spaces and the passages between them may be filled with the liquid synthetic resin through the tube 9, 55 the displaced air escaping through the vent 10. The whole may then be set aside or otherwise treated in a manner to produce a hardening of the spheres preferably under pressure to take up shrinkage. Large quantities of minute perfectly formed spheres will be cast at each "fill" 60 the said spheres being connected together by light webs of self material which may be easily broken off or removed by any suitable method. The particular advantage involved in making 65 the spheres, which function as spherical lenses, out of synthetic resin is that the focal point of the lens can be definitely fixed on its surface where it is embedded in the light reflective binder. The position of the focal point of any 70 sphere is dependent upon the index of refraction of the particular material out of which it is made and will be located on the surface when the index of refraction is 2.0. Where the reflective coating is on the surface of the sphere as in such 75 a sign, it is very important that the index of

refraction should be as close to 2.0 as possible but this is not feasible with glass except at a cost which would make it prohibitive commercially whereas by making the spheres out of synthetic resin the index of refraction can be easily 5 and cheaply controlled and fixed definitely at 2.0 by the addition of suitable salts to the solution when it is being compounded.

In Fig. 5 I have shown a novel and efficient form of a reflex reflecting element formed out 10 of transparent synthetic resin and adapted to be used and form an integral part with a binder paint or enamel containing a varnish gum capable of integrating by polymerization or hardening with the synthetic resin of said elements 15 as above described. This form of reflex reflecting element contains wholly encased within itself, however, the reflective material consisting of a spherical mirror. The upper and outer portion 12 of this reflex reflecting element is 20 in the form of a spherical lens equal in size to a complete hemisphere while the lower portion 13 is in the form of a cylinder of the same diameter as that of the said spherical lens with the concave spherical mirror 14 positioned 25 opposite said hemispherical outer surface and at the focal point of said lens. Said mirror is made preferably of thin metal silvered on its inner surface. In size it is slightly less than a complete hemisphere so that its circular edge will 30 not extend to the outside surface of the element. Where the synthetic resin of the element has been compounded to have a refractive index of 2.0 the said mirror will be constructed 35 on the same radius as that of the spherical lens 12 and its distance from the outside surface of the said spherical lens will be equal to the diameter of said lens, but where the synthetic resin has a refractive index of less than 2.0 the said mirror will be positioned a slight distance 40 further away and will be constructed upon a proportionately longer radius.

These reflex reflecting elements are constructed as follows: The stud 15 which may be of any suitably strong material having approximately 45 the same coefficient of expansion as the synthetic resin out of which the element is to be made or may be preformed of the same synthetic resin, is mounted in an upright position and to its end is fastened by a suitable adhesive 50 substance, the thin metallic spherical mirror 14 silvered in the usual way on its concave side, after which a quantity of transparent synthetic resin is molded about the mirror and said stud in the form above described by any suitable well-known means or method, the lower end of the stud 15 being utilized to hold the mirror 14 in its proper position in the mold. There is thus produced a reflex reflecting element in the form of a spherical lens having encased within it at 55 the focal surface of said lens a reflecting surface wholly protected from the atmosphere. These reflex reflecting elements should be preferably made in a size as small as possible and, after removing the protruding portion of the 60 stud 15 whereby it was held in position in the mold, a plurality of them may be arranged close to each other with their hemispherical surfaces uppermost to form the indicia of a sign and with their lower cylindrical portions embedded 65 in a layer of wet paint, lacquer or other substance as a binder material upon a supporting background, which binder material contains a varnish gum capable of integrating with the synthetic resin out of which said reflex reflecting 70

elements are made, and as has been hereinbefore described, the said binder in a similar way will completely unite with the cylindrical portions of the elements embedded in it so that 5 when the said binder has hardened they will be completely united with the said binder in an integral mass. When formed in larger sizes the protruding portions of the studs may be left in place and provide means for affixing said elements to a supporting background either by inserting them with a tight fit into perforations in the background support or by providing them with a thread whereby they may be screwed into the background support. 10

15 In Figs. 6 and 7 I have shown this same reflex reflecting element equipped with novel means for mounting it in a hole provided for that purpose in a supporting base consisting of a plate 16 of sheet metal or the like, the surface of 20 which may be enameled in any suitable colors and in a form to constitute a sign. The reflex reflecting element is molded in the same way but with an annular bead 17 surrounding its outer periphery substantially at the plane of division 25 between the hemispherical portion 12 and the cylindrical portion 13 of said element. The bead 17 forms a stop to limit the movement of the element through the hole in the plate 16. Anchored at their lower ends 18 in the cylindrical portion 13 of the element and extending upwards adjacent the outer wall of said cylindrical portion 13 are two ears 19 made of flat spring metal suitably disposed about said wall. Said ears are each formed with lower diagonal edges 20 and upper diagonal edges 21 and are curved or bent outwardly as shown in Fig. 6. The said 30 reflex reflective element may be forced through 35

a round hole in the plate 16 substantially the same size as the cylindrical portion 13 and as the said element is forced into the position shown in Fig. 6 the ears 19 will first be depressed and will then spring outward and engage the rear side of the plate 16. It will be noted that the upper edges 21 are inclined to the surface of the plate and curve outwardly, so that despite variations in the thickness of the plate 16 the ears will engage the plate and hold the 10 reflex reflecting element more or less rigidly in place. 5

It is obvious that many modifications may be made without departing from the spirit of my invention. For instance, the background may be 15 covered with the reflex reflecting elements leaving the insignia with a plain flat surface, or the entire surface of the sign may be covered and contrasting colors used to differentiate the insignia from the background. 20

What I claim is:

The method of making a reflecting device composed of a plurality of transparent, reflex reflecting elements partially embedded in an opaque light reflecting background substance 25 which comprises applying to a base a layer of plastic, opaque, light reflective binder material containing a varnish gum of synthetic resin capable of integrating by polymerization with synthetic resin elements subsequently to be applied, 30 partially embedding in said layer a plurality of reflex reflecting elements of such a synthetic resin, and substantially permanently joining the elements to the layer by polymerization of the varnish gum in the background layer. 35
